UNITED STATES PATENT OFFICE.

RUPERT E. RUNDELL, OF ROCKVILLE CENTER, NEW YORK, ASSIGNOR TO INTERNATIONAL CIGAR MACHINERY COMPANY, A CORPORATION OF NEW JERSEY.

REALIGNING DEVICE FOR CIGAR-BUNCH MACHINES.

Application filed January 12, 1924. Serial No. 685,793.

To all whom it may concern:

Be it known that I, RUPERT E. RUNDELL, a citizen of the United States, residing at Rockville Center, county of Nassau, and State of New York, have invented a new and useful Improvement in Realigning Devices for Cigar-Bunch Machines, of which the following is a specification.

This invention relates to a re-aligning device for cigar bunch machines. In making certain cigar bunches which are generally conical in shape, the bunch is produced in the usual way in a chianti belt mechanism and is then manipulated in the usual way in a conical manipulating device to which the bunch is transferred from the chianti belt mechanism. From the manipulating device the bunch must be transferred to other devices which act upon the bunch to complete it. In the manufacture of certain bunches of general conical shape, the bunch as it is delivered from the manipulating device is thrown out of alignment with the transferring device which must pick it up to carry it to the next mechanism operating on the bunch. The purpose of the present invention is to re-align the bunch as it is delivered from the manipulating device to eliminate the difficulty heretofore encountered in picking the bunch up for transport to another mechanism. With this and other objects not specifically mentioned in view, the invention consists in certain constructions and combinations which will be hereinafter fully described and then specifically set forth in the claims hereunto appended.

In the accompanying drawings, which form a part of this specification and in which like characters of reference indicate the same or like parts, Fig. 1 is a general elevation of a device constructed in accordance with the invention, the well known parts being shown more or less diagrammatically; Fig. 2 is a plan view of the structure shown in Fig. 1; and Fig. 3 is a detail perspective view of the re-aligning means.

In carrying the invention into effect, there is provided means for forming and manipulating a tapered bunch, a bunch transferring device for receiving bunches from the manipulating means and transferring them to another device further acting on the bunch, and means receiving the bunch from the manipulating means and re-aligning it for engagement with the transferring device.

The parts above mentioned may be widely varied in construction within the scope of the claims, for the particular device selected to illustrate the invention is but one of many possible concrete embodiments of the same. The invention therefore is not to be restricted to the precise details of the structure shown and described.

Referring to the drawings, 4 more or less diagrammatically indicates a chianti belt mechanism, the construction and operation of which is well known in the art. 5 indicates a table to which a bunch is delivered by the chianti belt mechanism. 6 indicates a pushing device which moves a bunch over the table 5 from receiving position 7 to delivery position 8, where it comes within the range of action of a manipulating device including a rotating conical member 9 and a stationary substantially concentric complementary member 10. The rotating member of the manipulator is provided with the usual peripheral grooves 11.

As the manipulation of the bunch is completed, the latter reaches a position in which it rests between the surface of the rotating manipulating member 9 and the ends of prongs 13 and 14. It is then out of alignment with a transferring device including spring actuated gripper fingers 15, 16, carried on the end of an arm 17 operated by means of a pinion 18 and a cam actuated rack 19 of well known construction and operation.

For the purpose of re-aligning the manipulated bunch so that it may with certainty be picked up by the fingers 15—16 of the transferring device, there is provided means for receiving the bunch from the manipulating means and re-aligning it for engagement with the transferring device. As shown, this means consists in a cradle having a bunch supporting section 20 which is in alignment with the fingers 15—16 of the transferring device. From the supporting section 20 extend two distorted fingers 21—22, the ends of which engage the grooves 11 of the rotating manipulating member 9. This cradlelike structure is supported by means of screws 23 engaging slots 24 in said structure, and a bar 25 carried on an arm 26, which is a well known part of the machine in connection with which the device is used. Assuming that a bunch is in the position 12, a slight further movement of the rotat-

ing manipulating member 9 causes it to roll out from under the prongs 13-14. It then falls on the fingers 21-22 and slides down the same, and becomes re-aligned during this sliding movement, so that the fingers 15-16 of the transferring device can readily pick it up when they are swung down into position to do so.

What is claimed is:

1. The combination with means for forming and manipulating a tapered bunch, of a bunch transferring device, and means receiving a bunch from the manipulating means and re-aligning it for engagement with the transferring device.
2. The combination with means for forming and manipulating a tapered bunch, of a bunch transferring device, and a cradle re-

ceiving a bunch from the manipulating means and re-aligning it for engagement 20 with the transferring device.

3. The combination with means for forming and manipulating a tapered bunch, of a bunch transferring device, and a sheet metal cradle having two distorted fingers engaging said manipulating means and receiving a bunch therefrom and re-aligning it for engagement with the transferring device.

4. A re-aligning device for a cigar bunch machine comprising a cradle having two 30 distorted fingers adapted to receive and to re-align a cigar bunch engaged thereby.

In testimony whereof, I have signed my name to this specification.

RUPERT E. RUNDELL.
